UNITED STATES PATENT OFFICE

PASQUALE MANCUSI, OF NEW YORK, N. Y., ASSIGNOR TO PURSMOKE PIPE COMPANY, INC., OF NEW YORK, N. Y., A COMPANY OF DELAWARE

TOBACCO PIPE

Application filed September 25, 1929. Serial No. 395,039.

My invention relates to new and useful improvements in a tobacco pipe and one of its objects is to improve the construction of the pipe shown and described in my co-pending patent application, Serial No. 279,070, filed May 19, 1928.

Another object of the invention is to simplify the construction of a pipe of this kind whereby a less number of parts are necessary to produce the device.

Another object of the invention is to so form the bottom closure that it will be less likely for the accumulated moisture to leak out.

A further object of the invention is to provide a pipe in which any moisture or saliva that tends to accumulate in the same will flow into the recessed closure and be prevented from entering the smoker's mouth when drawing on the pipe during smoking thereof.

A further object of the invention is to construct a tobacco pipe in a novel manner to provide a circuitous passageway from the tobacco bowl to the pipe stem.

A still further object of the invention is to so construct the pipe as to provide an integral partition between the pipe bowl and the recessed closure so as to define two distinct parts of the pipe bowl.

With these ends in view, this invention consists in the details of construction and combination of elements hereinafter set forth and then specifically designated by the claims.

In order that those skilled in the art to which this invention appertains may understand how to make and use the same I will describe its construction in detail, referring by numerals to the accompanying drawing forming a part of this application, in which:—

The figure is a longitudinal sectional view of a tobacco pipe constructed in accordance with my invention.

In carrying out my invention as herein embodied, 2 represents the main pipe bowl having an upper chamber 3 terminating short of the bottom of the pipe bowl, preferably at a point midway the length or height of the pipe bowl where there is formed a central cavity 4 surrounded by an annular groove 5.

The upper end of the pipe bowl is provided with means 6, such as threads, whereby the tobacco bowl 7 may be removably mounted therein, the latter being provided with complementary means, such as threads 8 for co-action with the threads 6.

The tobacco bowl is of cup-like formation and has an overhanging flange 9 so as to produce a groove 10 for registration with the upper end of the pipe bowl 2 and the side walls of the latter are preferably beveled to correspond with the beveled inner walls of the over-hanging flange on the tobacco bowl which will cause the tobacco and pipe bowls to snugly fit each other and reduce to a minimum the chances of drawing air between the two bowls during the smoking process. The lower portion of the tobacco bowl is tapered so as to be out of contact with the pipe bowl and provide a space of fairly large capacity 70 to receive the smoke prior to being drawn to the user's mouth and the extreme lower end of said tobacco bowl is apertured as at 11 for the passage of smoke from the burning tobacco. When the tobacco bowl is in place, 75 the lower end is directly above but in close proximity to the cavity 4.

The lower end of the pipe bowl has a large central recess 12 therein surrounded by a groove 13 so as to define a flange 14 provided with means 15, such as threads, whereby the closure 16 may be removably mounted, the latter being provided with complementary means 17, such as threads. The closure includes an exterior flange 18 which carries the 85 securing means 17 and suitably spaced from said flange on the inside of the closure is an annular vertical wall 19 to provide the recess 20 and the groove 21. When the closure is 90 mounted on the pipe bowl, the flange 14 enters the groove 21 and the wall 19 enters the groove 13, thus securely closing the lower end of the pipe bowl to prevent leakage. If found desirable, a packing washer 13a may be 95 placed in the groove 13.

The recess or bore 12 at the lower end of the pipe bowl terminates short of the chamber 3, thus providing a partition 22 between them, but as an integral part of the pipe bowl and 100

said chamber 3 and bore 12 are in communication through the aperture 23.

The pipe bowl is provided with a stem 24 having a socket 25 from which runs a branched passageway including an upper duct 26 inclined upwardly from the socket to the chamber 3 and a lower duct 27 inclined downwardly from the socket to the bore 12 for communication with the recessed closure and said lower duct is preferably of greater cross sectional area than the upper duct in order to take care of the combined accumulations of moisture from the upper duct 26 and the mouth piece 28.

From the foregoing description, it will be obvious that when tobacco is being burned within the tobacco bowl, smoke therefrom will be drawn into chamber 3 where it may circulate and finally pass through the upper duct 26 into the mouth piece and thence to the user's mouth. This circuitous flow of the smoke tends to reduce the temperature so as to be more pleasing to the smoker.

Any moisture which accumulates or tends to accumulate in the pipe bowl will flow directly into the recessed closure through the aperture 23 or will flow down the upper duct 26 to its junction with the lower duct from which point it will flow down the lower duct 30 along with any moisture which may come from the bore of the mouth piece, finally entering the recessed closure. When necessary or desirable, the recessed closure may be removed and cleaned of any moisture or any 35 foreign substance, thus keeping the pipe fairly dry and sweet.

Of course I do not wish to be limited to the exact details of construction as herein shown, as these may be varied within the 40 limits of the appended claims without departing from the spirit of my invention.

Having thus fully described my invention, what I claim as new and useful is:-

1. A tobacco pipe including a bowl recessed 45 at the upper and lower ends, a partition between said recesses in which is formed a large central cavity, a groove surrounding the cavity and an aperture to provide communications between said cavity and the lower 50 recess, a closure for the lower recess, a tobacco bowl removably mounted in the upper recess and a stem carried by said bowl and provided with two ducts leading from a common point to each of the recesses.

2. A tobacco pipe including a bowl recessed at its upper end to provide a chamber, said recess being so fashioned as to produce a large central cavity and a groove surrounding said cavity, said pipe bowl also being 55 recessed from the bottom end to define a central bore and a groove surrounding said bore, a flange projecting from the lower end of the pipe bowl, a partition within the pipe bowl between the end recesses and having an 60 aperture therethrough to provide communica-

tion between said end recesses, a closure having an exterior flange and a vertical wall spaced from said flange to produce a groove for registration with the flange at the bottom of the pipe bowl and said vertical wall registers with the groove in the bottom of the pipe bowl when the closure is in place, a tobacco bowl removably mounted in the chamber of the pipe bowl and having an over-hanging flange for coaction with the outer surface of the pipe bowl and a stem carried by the pipe bowl, said stem having two ducts leading from a common point at the outer end thereof to the interior of the bowl with one of said ducts communicating with the upper chamber in the pipe bowl and the other communicating with the lower recessed portion thereof.

3. A tobacco pipe including a bowl recessed at the upper and lower ends, a partition between said recesses in which is formed a large central cavity, a groove surrounding the cavity and an aperture to provide communications between said cavity and the lower recess, a closure for the lower recess, a tobacco bowl removably mounted in the upper recess and a stem carried by said bowl and provided with two ducts leading from a common point to each of the recesses, and a packing washer between the pipe bowl and closure.

In testimony whereof, I have hereunto affixed my signature.

PASQUALE MANCUSI.
